UNITED STATES PATENT OFFICE.

LEWIS LARSEN, OF MENOMINEE, MICHIGAN, ASSIGNOR TO HEYWOOD-WAKEFIELD COMPANY, OF BOSTON, MASSACHUSETTS, A CORPORATION OF MASSACHUSETTS.

DESIGN FOR A TABLE LAMP.

Application filed May 8, 1925. Serial No. 13,375. Term of patent 14 years.

To all whom it may concern:

Be it known that I, LEWIS LARSEN, a citizen of the United States, a resident of Menominee, county of Menominee, and State of Michigan, have invented a new, original, and ornamental Design for Table Lamps, of which the following is a specification, reference being had to the accompanying drawings, forming a part thereof, and wherein the figure is a perspective view of my new design.

I claim:

The ornamental design for a table lamp, substantially as shown.

LEWIS LARSEN.

Witnesses:

R. C. PAUL,
M. T. WHITTING.
